DESIGN.

F. MERION & M. HERTENSTEIN

HEATING STOVE.

No. 18,834.

Patented Jan. 1, 1889.

UNITED STATES PATENT OFFICE.

FRANK MERION AND MICHAEL HERTENSTEIN, OF COLUMBUS, OHIO.

DESIGN FOR A HEATING-STOVE.

SPECIFICATION forming part of Design No. 18,834, dated January 1, 1889.

Application filed July 11, 1888. Serial No. 279,866. Term of patent 3½ years.

To all whom it may concern:

Be it known that we, FRANK MERION and MICHAEL HERTENSTEIN, citizens of the United States, residing at Columbus, in the county of Franklin and State of Ohio, have produced a new and original Design for a Stove, of which the following is a specification, reference being had to the accompanying drawing, forming part thereof.

10 The perspective view of our newly-designed stove shows the front, one side, and a portion of the top thereof, this view being deemed necessary to illustrate the design desired to be shown.

15 The leading features of our design consist in the approximately-rectangular form of the stove, each of the four sides forming said rectangle presenting a slightly convex surface; in the ornamental design of feed-doors herein shown, and in the peculiar ornaments herein-after described made to appear on different parts of said stove.

20 In the photograph, A represents the front of the stove, and B one side thereof, the opposite side from the latter being an exact reproduction of the side B. The rear side of the stove, (not shown in the accompanying photograph,) although devoid of ornament, presents the same curved or convex outline as

30 the front and sides. The upper portion of the stove-body terminates in a flange or rim, c, overlapping each face of the stove, said rim being rounded outwardly and presenting at the center of its height a flattened raised band, d, and having the corners of said rim and band rounded or curved, as shown. The rim c is preferably ornamented above and below the central band, d, with raised representations of leaves, and is 35 surmounted by a cap, e, having a flat base and an upwardly and inwardly curved outer surface, upon the upper side of which may be made to rest any desired ornament, as shown at f.

40 Made to surround the body of the stove near the center of its length is a flanged rim, g, having rounded corners and having its portions between said corners curved outwardly to conform to the curve of the corresponding 45 faces of the stove.

The front face of the stove, immediately beneath the rim c, is provided with a half-circu-

lar ornamental plate, h, secured to the face of the stove and having suitable raised figures thereon. Beneath this plate h is a second oblong ornament-plate, h', having circular openings therein, in which are inserted suitable ornaments, h'', preferably of tile. 55

Any desired character of ornaments may be made to appear in relief on the front face of 60 the stove above the ornament-plate h.

The side faces, B, are each formed with the representation of two ornament-plates, b b', corresponding in position and general outline with the plates h h'. Below each of the plates b' and h' is a feed-door, B' A', consisting of a frame and "open-work" face, as hereinafter described. Extending transversely across the center of the door-frame is a bar, i, and crossing said bar i, at equal distances from the 70 center of its length, are two vertical bars, k, connecting the upper and lower side of said frame. Formed with said bars is an open ring, k', the latter cutting the bars i and k at points near their extremities within the outer 75 frame of the door. The ring k' has formed thereon at intervals ornamental projections k''. The front side of the stove, beneath the rim g, is provided with suitable draft and ash doors, m m', which may be formed with any 80 desired ornaments. Each of the sides B, beneath the rim g, have formed thereon two ornamental panels, l and n, each consisting of a raised frame and inclosing a suitable design of flowers and scroll-work. The corners of 85 the body of the stove are each rounded in the representation of a column.

The enlarged stove base-plate p has its top side flattened and from the edge of its flattened portion extends outward and downward 90 in a curved line, having its corners rounded, as shown. The legs q are connected, as shown, by ornamental plates r, the latter having in relief thereon suitable scroll and other ornamental designs. 95

The plates h h' b b' and doors above described are all curved outward to conform to the convex form of the stove sides and front.

A name-plate, as shown on the front side of the base p, may be made to bear any desirable name. 100

Having now fully described our design, what we claim is—

1. The design for a stove herein shown and

described, consisting of a rectangular body having convex faces with feed-doors B' , having a horizontal cross-bar, i , two vertical bars, k , crossing said bar i , a ring, k' , uniting said bars k and i , and ornamental projections k^2 upon said ring, and above the front feed-door a curved plate, h' , having circular openings with ornaments h^2 inserted therein, and above the plate h' a semicircular plate, h , having ornaments thereon, and above the body of the stove a projecting band, d , with a rounded rim ornamented with raised representations of leaves above and under said band, the whole surmounted by a cap, e , having an upwardly and inwardly curved surface and an ornament standing thereon, under the feed-doors a flanged rim, g , and below said rim the body having ash-doors m m' , and said body resting upon a large base-plate, p , having a name-plate on the front side, the whole resting upon legs q , connected by plate r , having scrolls and ornamented designs in relief thereon.

2. In a design for a heating-stove herein shown and described, the rectangular body having convex faces with front feed-doors, B' , and above said doors the curved plate h' , having circular openings with ornaments h^2 inserted therein, and above the perforated plate h' a plate, h , having its upper portion semicircular and ornaments in relief thereon. 25

3. In a design for a heating-stove herein shown and described, having a rectangular body with convex faces, the feed-doors B' , having a central horizontal cross-bar, i , two vertical bars, k , crossing said cross-bar i , a ring uniting said bars k and i , and ornamental projections k^2 upon said ring between the points of attachment of the cross-bars. 30 35
